TOP FOR PERCOLATORS AND THE LIKE

Emiel P. Seghers, Chicago, Ill.

Application July 12, 1928, Serial No. 292,278

44 Claims. (Cl. 53—3)

This invention relates to covers for percolators or similar vessels, comprising a lid and a glass top, and has for one of its objects the provision of means whereby the glass tops are retained in place in the lid without danger of being loosened by heating or cooling, the retaining means being arranged to permit easy removal of the top, when desired.

10 Another object is to provide a percolator top which is economical to manufacture, of improved construction, and efficient and convenient in use.

Another object is to provide a convenient retaining means for holding the top in place, and with both the construction of the top and the retaining means so arranged as to co-operate with one another toward a common end.

Another object of this invention is to provide resilient retaining means arranged between the top and lid of the cover for retaining the top in operative position with respect to the lid while permitting the top and lid to expand and contract at different rates without damage to the top and without impairing the utility of the retaining means.

25 Another object of the invention is to provide resilient retaining means which can be used with standard percolator tops as well as with the improved tops shown herein.

Another object is to provide a separate ring for 30 retaining the top and the lid in co-operative relation with each other, the ring being preferably provided with means for removably securing the same to the lid and including resilient means engaging the lid and/or top so as to compensate for unequal expansion and contraction of said top and lid.

Another object is to provide a glass top having a depending flange with a recess below the outer peripheral surface thereof for the reception of 40 a retaining means either separate from the lid and top or affixed thereto or carried thereby, the retaining means comprising preferably a continuous ring having portions thereof adapted to engage the underside of the lid and other portions arranged within the recess to engage an upwardly facing shoulder or abutment surface forming a wall of the recess to prevent separation of said top and lid.

45 A still further object of this invention is to provide a top having a depending apron or flange, with a downwardly and outwardly sloping face adapted to be engaged by a yielding retaining means on the lid or arranged between the lid and top whereby upon the relative expansion and contraction of the top and lid, the resilient means

may slide over the downwardly and outwardly sloping face to prevent damage to the top while at the same time maintaining proper operative relationship between the top and lid.

Another object of this invention is to provide 5 resilient means for holding a glass top in the lid of a percolator cover with freedom of expansion and contraction while at the same time providing means for resisting or preventing relative rotation between the same.

The invention is exemplified in the combination and arrangement of parts shown and described herein and it is more particularly pointed out in the appended claims.

Fig. 15 is a detail view in cross-section of that form of the top shown in Fig. 14;

Fig. 16 is a detail view of a portion of a percolator top showing the form of lug illustrated in 5 Figs. 14 and 15; and

Fig. 17 is a perspective view of the clip shown in Fig. 3.

Referring now to the drawings in detail and more particularly to Figs. 1 and 2, 5 represents a 10 container lid which is adapted for use in connection with comparatively large coffee urns or percolators and like containers, said lid being usually made of a non-resilient metal such as aluminum. The metal lid 5, as is customary in 15 devices of this kind, is made with a central opening surrounded by a depending flange 6 and the percolator top 7 usually of glass, is interlocked in the opening in the lid by means of a bayonet joint comprising lugs. As shown in Fig. 10, this bayonet joint may be made by providing notches 8 at 20 diametrically opposite points in the peripheral edge of the central opening and in the depending flange 6 so that the laterally projecting lugs 9 at the opposite sides of the apron 10 of the top, 25 having the configuration shown in the drawings, may be registered with these notches to seat the projecting lugs 9 below the edges of the flange 6; then, by turning the top 7, moving the projecting lugs 9 out of registration with the notches 8.

30 In my improved construction, I provide means other than the bayonet joint for retaining the top in place. I have found in practice that the bayonet joint alone is insufficient for holding the top in place for the reason that when the hot coffee or other liquid percolates into the top 7, the top, 35 being made of glass, expands and enlarges the opening in the lid, which is made of metal which will yield readily. The lid, usually being made of aluminum, is not as resilient as it should be to 40 compensate for the expansion of the top. As a result, after the opening has been enlarged and when the top cools off, the opening is too large and the top then is freely rotatable so that it is 45 very apt to rotate until the projecting lugs 9 register with the notches 8 and the top will then fall out of the lid or the container when it is tilted. Furthermore, the expansion of the glass top 7 is very apt to spread the opening to such an extent that the top will rotate while the coffee is 50 percolating against it, which will cause the same to rattle.

55 Still another disadvantage of any device which relies entirely upon the bayonet joint to retain the top in place, is that the lugs, being comparatively short and having a small point of contact with the edge of the depending flange 6, makes it possible to easily pull the top out of the opening regardless of whether or not the projecting lugs are in registry with the notches 8. As a matter 60 of fact, practice has shown that the opening in the lid has sometimes become so enlarged that the top will even fall out without the projecting lugs 9 being in registry with the notches 8.

To overcome these and several other disadvantages in relying solely upon the bayonet joint arrangement to hold the top 7 in place, I have devised means other than the bayonet joint to retain the top in place and hold the same against rotation at least to the extent that it will not rotate without the application of manual force thereto.

According to Fig. 1, the top retaining means, in addition to the bayonet joint arrangement, comprises one or more depending spring tongues, 75 clips or fingers 11. These are riveted or other-

wise fastened, as at 12, to the underside of the lid on the outside of the boundary of the depending flange 6. These tongues are presented at a slight angle to the depending flange 6 and in position to engage the projecting lugs 9. The engagement between the spring tongues 11 and the projecting lugs 9 may be made by providing perforations 11' in the spring tongues, in which perforations the lugs seat, or else open slots in the edges of the spring tongues may be used as described later in connection with Fig. 13. These two possibilities are illustrated in Figs. 2 and 13 respectively, the slot being indicated by the reference character 51. With the construction so far described, by placing the top 7 in the opening in 15 the lid and rotating the same, the lugs 9 will wipe against the spring tongues 11 and when they register with the holes or slots therein, the resistance offered by the spring of the metal of the tongues will snap the lugs 9 in the closed openings 11' or slots 51 and arrest rotation of the top. The top will thus be held against rotation but it may be rotated by manual effort so as to disengage the lugs from the tongues so that the top may be rotated to register the lugs with the 20 notches 8 for removing the top.

It will thus be seen that by applying one or more of these spring tongues to the lid, I provide means in addition to the bayonet joint arrangement for holding the top against rotation and for preventing its accidental displacement out of the opening. The resiliency of the metal of the spring tongues and the fact that the lugs 9 are tapered or conical in shape, will compensate for the expansion of the top when it is heated 35 because the lugs will have a certain limited movement in the openings of the tongues against the resistance offered by the resiliency of the 40 tongues.

For very large coffee urns or percolators, I propose to employ an extra pair of spring tongues 13 which may be either riveted to the top of the lid by rivets 12, or else riveted to the underside of the lid, as illustrated in Fig. 1, with their ends projecting through openings in the lid and 45 terminating in hooks which will ride over the serrated or wavy edge 14 of the radial flange 15 which is formed as an integral part of the top 7 just below the dome thereof and above the apron 10. The underside of this flange provides 50 a ledge which rests upon the peripheral edge of the opening in the lid and acts as a stop for limiting the downward movement of the top into the opening. It will thus be seen that the flange is confined between the retaining tongues 13 and 55 the peripheral edge of the central opening in the lid. The resiliency of the spring tongues 13 holds the top against the edge of the opening under tension, making a close, intimate contact between the edge of the opening, preventing sediment from getting between the edge of the opening and the top and also making a good contact for transferring the heat of the lid to the glass top. Consequently, the top, instead of being heated suddenly, when the coffee or other liquid 60 percolates against it, will gradually be heated prior to the percolating of the coffee or other liquid by having the heat of the lid transferred to it, as explained.

In the old form, where the top was loosely 70 mounted in the opening, any sediment between the top and the edge of the opening would insulate the top from the lid and as a result, the top would stay practically cool until the coffee or other liquid percolated against it; then, being 75

heated suddenly, it would expand and crack. The spring tongues 13 will be made out of metal which is resilient to compensate for expansion and contraction of the top and lid relative to each other, and, after the top is cooled off and contracted, the tongues will still retain the top against the edge of the opening under tension.

- As a further feature of the retaining means for holding the top in the opening in the lid, I propose to form a circular depression or recess by configuring the lower part of the apron of the top with a beveled side 16 which terminates in a short outwardly and downwardly beveled surface 17 which in turn terminates in a ledge, projection or abutment 18. This ledge 18 is slanted in opposite directions from the diametrically opposite sides of the apron and each slanting length of the ledge terminates in a block-like radial area 19, the surface of which is flush with the outside circumference of the ledge 18. The projecting lugs 9 are formed on the surface of this area 19 and the end walls 20 of the area 19 are beveled peripherally so that the tongues 11 ride up over the surface 19 and snap over the lugs 9. When the top is first inserted in the opening, the spring tongues 11 occupy a position close to the beveled surface 16 with the lower edges thereof resting upon the ledge 18 so that as the top is rotated, these lower edges of the tongues wipe across the ledge until they ride up over the surfaces 19 of the raised areas on the apron. In order to accommodate the spring tongues or fingers 13, the radial flange 15 is interrupted as at 21 at diametrically opposite points on the top. In the event that the projecting lugs 9 are not employed or should one or both of them be broken off, the edges of the spring tongues 11 will engage the beveled side 17 and hold the top in place, and the bevel will allow for expansion and contraction. When the top expands, the edges of the spring tongues may slide on the beveled surface 17 and thus compensate for expansion. The ledge 18 with its upper substantially horizontal surface is simply an emergency stop to prevent withdrawal of the top from the opening without first registering the projections 9 with the notches 8. It is, of course, understood that when the projecting lugs 9 are not employed, the notches 8 will not be required.
- In Fig. 3, I have illustrated an ordinary commercial type of percolator top 7a and shown the use of the same in combination with my improved retaining device. The retaining device, in this respect, is riveted, as at 12a to the lid 5a so that the spring tongues 11a are presented substantially parallel with the depending flange 6a in a position to engage the projecting lugs 9a on the apron 10a of the top. Of course, in using the projecting lugs 9a, notches such as 8 shown in Fig. 10 are provided in the peripheral edge of the opening in the lid, to enable the top to be inserted within the opening; then, by turning the top, the projecting lugs 9a wipe against the spring tongues, pressing them outwardly against the resilient resistance of the metal of the tongues and seating in the openings therein, as explained with reference to the co-operating spring tongues and projecting lugs in Figs. 1 and 2.
- As illustrated in dotted lines in Fig. 3, the holes 62 in the spring tongues 11a which receive the projecting lugs 9a are slightly larger than the lugs so as to allow for a limited vertical movement of the lugs in the openings with the movement of the lugs on the beveled face so as to

compensate for expansion. It is, of course, understood in connection with the illustration in Fig. 3, that where I have shown two of the tongues 11a, one may be sufficient in some instances. In this connection, it should be pointed out that where one spring tongue is employed, the resilient tension of the same will hold the opposite projection against the edge of the depending flange 6a.

In Fig. 4, I have illustrated substantially the same type of spring fingers 11b except that they do not necessarily have the openings for the reception of the projecting lugs 9, the reason for this being that the projecting lugs are not required. Instead of using the projecting lugs to co-operate with the spring fingers, I make a special type of percolator top 7b, the difference being that the apron 10b is configured with a plurality of spaced notches or recesses 22 and 27 each having undercut rounded beveled surface 23 terminating in an outwardly and downwardly slanting bevel 24 which, in turn, terminates in an arresting ledge 25 which will serve in the same capacity as the ledge 18, referred to in Figs. 1 and 2. Alternate ones of these notches or recesses 22 are made with converging or beveled opposite side walls 26. The intermediate ones 27 of the recesses are not so constructed, and, for instance, as illustrated by the similar notch 27c in Fig. 5, have straight sides at substantially right angles to the outer surface of the apron 10b. The function of the straight sided notches or recesses 27 will be hereinafter referred to.

In applying the top 7b in the form of the invention shown in Fig. 4, since there are no projecting lugs employed, the notches, such as 8 in Fig. 10, may be dispensed with so that the top is simply inserted in the opening and then rotated, with the spring tongues wiping across the flush surface of the apron 10b until they are seated in the recesses or notches with their lower edges contacting with the beveled lower walls or surfaces 24. The reason for using alternate ones of the notches with straight sides and beveled sides, respectively, is to accommodate the top 7b in percolators in which the lids are either hinged or have a slip top so to speak. Where the lid is a slip cover, as shown in Fig. 4 at 5b, the tongues will seat in the straight sided notches such as 27, and after once seating in the same, the spring tongues cannot be removed by turning. Therefore, the top 7b is fixed to the lid to such an extent that it may be used as a handle for pulling the lid out and turning the lid to make the removal of the same easier. Whenever it is desirable to remove the spring tongues from these straight sided notches, an instrument suitable for the purpose may be inserted under the edges of the spring tongues, and, to leave the edges accessible for this purpose, the lower end wall of each of the notches or recesses is made with an undercut recess or inclined groove 28, so that the instrument may be inserted for springing the tongues out of the notches 27. For those types of lids which are hinged to the percolator, the spring tongues may seat in the notches 22 which have the beveled sides 26 and these latter sides will cam the tongues out of the notches onto the outer flush surface of the apron 10b on rotating the top.

In Fig. 5, I have illustrated the same type of top as in Fig. 4 except that it is one which is especially adapted for large percolators where additional retaining means, such as spring fingers 13 in Fig. 1, are employed. In this con-

nection, the radial flange 15c, instead of being wavy as is the flange 15 in Fig. 1, is made with edges 29 and 30 which are slanted in opposite directions from the diametrically opposite sides 5 of the top. Parts 22c, 23c and 28c correspond to similar parts 22, 23 and 28 in Fig. 4. It is of course to be understood that the construction of the radial flange 15c may be employed on the top without co-operating use of the notches or recesses 22 and 27. In other words, spring fingers or tongues such as 13 may be employed in the combination with the radial flange 15c as the sole means of retaining the top in place. In this instance, the apron will be preferably plain, 15 as shown in Fig. 3, and even without the projecting lugs such as 9.

In Fig. 6, the top 1d is made with an apron 10d, one surface of the circumference of which bears against the depending flange 6d of the lid 20 5d with the lower surface having a continuous bevel as at 31 which terminates adjacent the edge of the apron in peripherally slanting or beveled surfaces 32 and 33 which extend in opposite directions from the diametrically opposite 25 sides of the top forming an annular shoulder. Or considering it otherwise, an annular circumferentially extending recess is provided between the bead 60 and the ledge formed by the surfaces 32 and 33, the recess being below the outer circumferential surface of the flange or apron 10d. These surfaces provide ledges against which the ends of the spring tongues 11d contact. The spring tongues, in this form, are hinged, as at 34, to short mounting plates 35, which are riveted 30 as at 12d, to the lid 5d. The space between the depending flange 6d and the top of the lid 5d provides an annular recess under the lid in which the hinges 34 for the spring tongues 11d are free to move, the hinges in this respect being urged upwardly by the leaf springs 36 which are riveted 40 as at 12d.

Since the edges of the spring tongues 11d bear against the ledge made by the surfaces 32 and 33, expansion of the top 1d will exert a thrust on 45 the spring tongues, and, were it not for the resiliency of the tongues and the space behind the depending flange 6d in which they may move, the expanding action of the top would be very apt to snap or break off the ledge provided by the 50 surfaces 32 and 33. To avoid this, the hinges for the spring tongues and the space in which the hinges are free to move, are provided. At the meeting ends of the surfaces 32 and 33, the ledge has a beveled lifting surface 37 which will 55 cause the spring tongues to ride onto the surface of the apron so that the top may then be lifted out of the opening.

In Figs. 7 and 9, I have illustrated still another form of retaining means for holding the 60 top 5e connected to the cover by the use of a ring formed of spaced fingers 38 connected at their upper ends to form an annular continuous inextensible ring, the same being formed with a rolled edge 39 forming an annular groove on the 65 outside of the ring to receive the edge of the opening in the lid 5e. This form of my invention is especially adapted for use in connection with porcelain, enameled or similar covers, which are 70 easily chipped and are, therefore, unsuitable to accommodate rivets as in the other forms described. However, the use of this form of my invention is not limited to such containers.

In Fig. 7, I show a top 7e in cover 5e. This 75 cover can be made of any class of material but its greatest use is with covers which are of material

too hard to be flexed or deformed without injury, like in a porcelain enameled steel, which will not flex or deform without chipping, or, with soft material like aluminum, which is too soft to be flexed to a permanent position and exert enough pressure to hold the top in position in the cover, when the percolator is in use, thus to prevent the top from falling out of the opening in the lid onto the floor.

Experience has shown that the depth of the 10 depression formed by the rolled edge 39 should be no more than one-half the thickness of the metal the cover is made from. When aluminum is used the thickness of the cover is about 1/64 inch, thus the depression would not be more than 15 1/128". When aluminum is used it is possible to make the holes or openings in the percolator lids nearly the exact diameter of the bottom of the recess in the rolled edge of the ring. The 20 aluminum will "give" sufficiently to enable the ring to be snapped into position within the opening either while the ring is on the top or separate therefrom. The ring can be inserted in the 25 opening either from the under side or upper side of the cover.

The ring can be first placed on the top about the apron thereof and in this position the ends of the spring fingers 38 will contact the beveled surface 42 or the stop ledge 43. The top, with the ring thereon, can then be inserted in the 30 opening in the lid and by a slight pressure on the top the outwardly projecting bases of the spring fingers 38 will yield inwardly and permit the edge of the opening in the lid to snap into the recess in the edge of the ring. Note that the spaces 35 between the adjacent fingers 38 extend high enough to practically reach the bottom of the groove or recess formed in the edge of the ring. These projecting fingers on the ring, therefore, have means for contacting not only the upper 40 side of the ledge 43 but also have means for engaging the under side of the lid 5e so that even if the portion of the ring lying above the lid of the percolator were not present, the ring would still 45 be effective to prevent the top from being removed from the cover.

It will be clearly seen that in cases where the 50 opening in the cover is too small, or in cases where the ring is too large, or is deformed out of shape as compared with the opening in the cover, the apron of the top can be placed in the opening and then the ring slipped onto the apron until the lower ends of the tongues 38 of the ring 55 snap into place within the depression in the apron and will be held in place by the configuration 42 or 43, the upper portion of the ring contacting the under side of the cover to hold the top in place.

This last mentioned method of employing the 60 ring can be used with percolators now in use and having depending flanges around the openings in the lids thereof, such as in Fig. 6. By making the ring slightly larger in diameter than the flange 65 on the lid, the ring can be slipped over the apron of the top, and then over the flange on the cover until the spring fingers 38 snap in place and the upper portion of the ring contacts the cover.

In the use of the ring with porcelain enameled 70 lids, it is very difficult to get the enamel around the edges of the opening to be of even thickness. Thus the opening is at times too small for the ring to pass into. This makes it necessary to employ the method set forth in the second paragraph above.

In Fig. 8, substantially the same retaining de- 75

vice is illustrated as in Figs. 7 and 9 except that the ring is made as an integral part of the depending flange of the lid 5f, instead of being separately formed as shown in Figs. 7 and 9. This form of the invention is well suited to more or less expensive percolators or other such devices in which the lid 5f is constructed of brass or other sheet metal which will offer sufficient resiliency.

One form of top 1e that may be used in combination with the retainers shown in Figs. 7, 8 and 9, is illustrated in Figs. 7 and 8. The top in this connection has an apron 16e with a beveled annular surface 41 terminating in an outwardly beveled surface 42 which, in turn, terminates in a ledge 43. The block-like restricted areas 44 at diametrically opposite sides of the top will be provided with the projecting lugs 9e, as in the other form of top shown in Figs. 1 and 2, and these lugs are intended to seat between the fingers 38 or 38f and in the complementary squared notches 45 at the lower terminations of the slits 46 which divide or separate the fingers. The ring, in all the three forms shown in Figs. 7, 8 and 9, will be made with opposed notches 8' substantially like the notches 8 shown in Fig. 10, so as to accommodate the projecting lugs 9e when the top is inserted in the opening of the lid.

While the ring shown in Fig. 8, of course, cannot be rotated, being an integral part of the lid, the separately formed rings shown in Figs. 7 and 9 may possibly rotate and for this reason, at opposite sides of the peripheral edge of the opening, I provide notches corresponding to the notches 8' so that the metal which forms the notches 8' in the collar will seat in the notches in the edge of the opening and lock the ring against rotation.

In inserting a top in place in this form of the invention, it will be rotated until the projecting lugs 9e are seated between the fingers. The reason for rotating the top before letting the projecting lugs 9e come to rest between the fingers, is to make the lugs out of registration with the notches 8'. Otherwise, all that would be necessary would be to insert the top in place and it would seat between the fingers. The resiliency of the fingers and the spaced relation of the same provided by the slits 46, divide the resilient tension in the fingers so that they grip the lugs 9e and securely hold the top in place.

As an added advantage of the spring fingers 38, it will be possible to bend two of them inwardly, as shown in Fig. 7, so that their lower edges will wipe against the outwardly beveled annular surface 42 and thus retain the top in place without the lugs 9e. To release the top from this particular retainer, it would be rotated until the two spring fingers come in contact with the beveled sides 48 of the block-like areas 44 which would enable them to ride onto the surface of the said areas, after which the top could be withdrawn. The fingers 38 which are bent inwardly would function in substantially the same capacity as the spring tongues 11b in Fig. 4 and previously described.

Figs. 11, 12, 13 and 17 illustrate four modifications of spring tongues, for instance, in Fig. 11, the spring tongue 11h, provided with the opening or perforation 65, is shown with an integral rivet 49 which may be used in lieu of the rivets 12.

In Fig. 12, the spring tongue 11g is shown with an intermediate web 50 which will permit an instrument to be inserted under the tongue to lift it up. This will be useful where a ledge,

such as 43 or 33, is employed on the top. It will also be useful where a top is provided with notches, such as 22 and 27, Figs. 4 and 5. It will co-operate in this instance very nicely with the undercut notches or inclined grooves 28 and 29c shown in those figures.

In Fig. 13, the tongue 11n is shown with an open slot 51, instead of the round opening 65 shown in Fig. 11. This open slot will straddle the projecting lugs and the engagement between the tongues constructed with the open slots and perforations will be substantially the same.

In Fig. 17, the spring tongue 11k is crimped, as at 52 and has a perforation 62. This particular form of tongue is shown in the assembly view in Fig. 3 and it will be noted that it embraces the projecting lugs 9a in a slightly different manner than where a crimp is not used. The stiffness added to the tongue by the crimp increases the tension of the engagement and it also grips a greater area of the lugs than without the crimp, when the lugs ride under the spring tongues having the crimp 52. If the lug is in the crimp but out of the opening 62, the spring tongue will still resist upward movement of the top.

By providing the crimp, the end of the tongue around the opening therein substantially corresponds to the cross-section of the lug so that when the tongue moves out on rotation of the top, it does not move as far out of its normal position as with other forms of spring tongues illustrated.

In Figs. 14, 15 and 16, I have illustrated a top with a modified form of projecting lug. The lug 53 in this form, is cup-shaped and is molded as an integral part of the apron 10m of the top 1m. The retaining device which may be used with this lug is shown in Fig. 14 and comprises a spring tongue 11m, but since the end of the tongue seats within the lug, it need not be provided with an opening or slot as illustrated in connection with the other tongues.

Where the spring tongue 11a is held in place by a rivet as shown in Fig. 3 at 12a, it is possible that the tongue may turn. To prevent this turning movement, the depending flange 6m of the lid may be made with a hump, such as 54 (Fig. 14), to provide a bearing surface for the tongue and resist any tendency that it may have to rotate about its single pivot.

It is, of course, understood that the particular cooperative relationship of the parts as illustrated is not necessarily confined to the arrangements shown in the drawings, as many of the parts are interchangeable so as to provide both a top and a retainer therefor for many different specific purposes.

It is understood that in the specification and in the claims, that wherever reference is made to "spring" clips, tongues or retaining means, or to "resilient" means, or similar means, that applicant is using these terms in the sense that they imply a means that is capable of being deflected out of its normal position and will return to its normal position again automatically unless restrained, without material permanent distortion as in the case where a soft metal is used, such as aluminum, tin, or the like. In other words, when it is deflected out of its normal path, energy is stored up therein and this results in a yielding force tending to return the means to its normal position. This causes gripping of the percolator top or lugs and permits one to insert and remove a percolator top many

times without destroying the operativeness of the "spring", or "resilient" means.

Obviously, those skilled in the art may make various changes in the details and arrangements 5 of the parts without departing from the spirit and scope of the invention as defined by the claims appended, and I, therefore, do not wish to be restricted to the precise construction herein disclosed.

10 Having thus fully described my invention, what I claim and desire to secure by Letters Patent of the United States is:

1. A container lid having an opening therein, a glass top having an apron fitting into said opening, an annular shoulder on said top for limiting the movement of said apron into said opening, downwardly and inwardly projecting spring clips on said lid at opposite sides of said opening, and diametrically disposed lugs on said 15 top for engaging said clips to frictionally hold the top connected to said lid.

2. In a percolator cover, the combination with a lid having an opening therein, of a glass top having an apron adapted to fit loosely in said 25 opening, a lug on said top projecting laterally from said apron, and a spring clip connected to said lid in position to engage said lug and having means thereon co-operating with said lug to hold the top connected to the lid while permitting relative movement therebetween sufficient to compensate for unequal expansion of said top and lid.

3. A percolator cover comprising a lid having an opening therein, and a resilient clip projecting downwardly and inwardly from the edge of said opening and adapted to hold in said opening a glass top having a lateral projection thereon, said clip having means to releasably engage said projection to resist removal of said top from said 35 opening.

4. A percolator cover comprising a lid having an opening therein, and a plurality of spaced resilient perforated clips adapted to engage a glass top having a lateral projection forming a 45 retaining shoulder, when said top is in said opening, said clips having portions projecting toward the center of said opening in position to have their lower ends engage said projection on said top.

5. In a percolator cover, the combination with a ring lid, of spring clips projecting downwardly from the edge of the opening in said lid, a glass top having an apron adapted to fit loosely into said opening, a beveled recess retainer in said 55 apron to co-act with said spring clips to hold the top in said opening, and means on said apron to co-act with said clips to release the latter from said retainer upon turning the top relatively to said lid.

6. In a percolator cover, the combination with a lid having an opening therein, of a glass top having an apron adapted to fit loosely in said opening, a recess in said apron having a beveled lower portion, and a spring clip connected to said lid in position to extend into said recess and engage the beveled surface thereof to hold the top in said lid while the lower end of said clip is free to ride over said beveled surface during expansion and contraction of said lid relatively to said top.

7. In a percolator cover, the combination with a lid having an opening therein, of a glass top having an apron fitting in said opening, a resilient retainer attached to said lid, a recess in said apron having a lower beveled surface, said

retainer being adapted to extend into said recess and engage said beveled surface, and a stop ledge for engaging said retainer to prevent the removal of said top from said lid.

8. In a percolator cover, the combination with a lid having an opening therein, of a top having an apron fitting into said opening, a recess in said apron with its lower surface beveled downwardly and outwardly, a spring clip on said lid in position to extend into said recess, said clip upon expansion of said top relative to said lid being adapted to ride over said beveled surface and thereby relieve the strain of said expansion on said top, a stop ledge below said beveled surface for preventing removal of the top from said lid, and a recess in said stop ledge for the insertion of an instrument under said clip to pry the same free from said stop ledge when said top is to be intentionally removed from said lid.

9. In a percolator cover, the combination with a lid having an opening, of a glass top having an apron adapted to fit the opening in said lid, a recess in the apron having a lower beveled surface and a lateral beveled surface, and a spring clip on said lid in position to extend into said 20 recess and engage said beveled surface.

10. In a percolator cover, the combination with a lid having an opening therein, of a glass top having an apron fitting within said opening, a plurality of spaced recesses in said apron, alternate ones being provided with straight side walls and all provided with beveled lower surfaces, stop ledges below the lower beveled surfaces, and a spring clip on the lid adapted to project into any one of said recesses, one of said ledges having a recess therein for the insertion of a tool to pry away the spring clip sufficiently from said ledge to allow intentional removal of the top from said lid.

11. A glass percolator top having an apron, 40 a recess in said apron having a lower beveled surface adapted to be engaged by holding means on a lid, and a stop having a substantially horizontal surface extending from said beveled surface to prevent accidental removal of said top 45 from said lid.

12. In a percolator cover, the combination with a lid, of a glass top having an apron fitting an opening in said lid, a recess in said apron with the lower portion of said recess beveled 50 downwardly and outwardly, a spring clip on said lid in position to project into said recess when the top is connected to said lid, and a stop having a horizontal surface extending laterally from said beveled surface, said stop having a recess 55 therein for the reception of a tool under the lower end of said spring clip, whereby said clip can be released from said stop.

13. A glass percolator top having an apron with a recess therein within the thickness thereof, 60 said recess having side walls at substantially right angles to the surface of the apron, and a lower wall extending inwardly from the surface of the apron at substantially a right angle and then at an inclination thereto, said portion which is at 65 substantially right angles having an inclined groove therein.

14. A glass top for percolators having an apron and a recess within the thickness thereof, said recess having the lower wall thereof formed with 70 one portion at substantially right angles to the surface of the apron and another portion at an angle to the latter portion, the first portion having an inclined groove therein substantially in alignment with the second mentioned portion. 75

15. A glass percolator top comprising an apron having a recess therein and an outwardly and downwardly inclined portion forming a stop ledge adapted to engage a spring on a percolator lid 5 to hold the top in said lid.
16. In a cover for a percolator, the combination with a lid having an opening therein and depending spring clips on said lid near said opening, of a glass top having an apron extending 10 into said opening, and projecting means on said top slidably co-operating with means on the spring clips to hold said top in said opening but permitting relative movement sufficient to compensate for unequal expansion of said top and lid. 15
17. A percolator cover comprising a lid having an opening therein, provided with a resilient clip adapted to engage and hold in said opening a glass top having means thereon for inter-engagement with said clip. 20
18. In a percolator cover, the combination with a lid having a circular opening therein, of a glass top having a depending cylindrical flange thereon fitting within said opening and having an 25 outside diameter no greater than the inside diameter of said opening, said flange having a circular circumferentially disposed recess therein below the outer surface thereof, of a ring separate from said lid and top surrounding said flange and having a portion thereon abutting against the lower side of the edge of said lid surrounding said opening and a portion arranged within said recess to prevent removal of said top. 30
19. In a percolator cover, the combination with 35 a lid having a circular opening therein, of a glass top having a depending cylindrical flange thereon fitting within said opening and having an outside diameter no greater than the inside diameter of said opening, said flange having a circumferentially disposed recess therein below the outer surface thereof, of a resilient ring separate from said lid and top surrounding said flange and having a portion thereon abutting against the lower side of the edge of said lid surrounding said opening and a portion arranged within said recess to prevent removal of said top, said recess having a sloping surface presented to engage said latter portion of said resilient ring to compensate for unequal rates of expansion of said top and lid and to hold said top firmly in said opening. 45
20. In a percolator cover, the combination with a lid having an opening therein, of an annular ring arranged within said opening and having a portion adapted to receive the edge of said lid surrounding said opening to hold said lid and ring in fixed relation to each other, a glass top having a flange fitting within said ring, said flange having a recess therein, and means on said ring arranged within said recess. 50
21. In a percolator cover, the combination with a lid having an opening therein, of an annular ring arranged within said opening and having a portion adapted to receive the edge of said lid surrounding said opening to hold said lid and ring in fixed relation to each other, a glass top having a flange fitting within said ring, said flange having a recess therein, and spring fingers on said ring having the ends thereof engaging within said recess for yieldingly holding said top firmly within said opening with freedom of expansion and contraction relative to said lid. 55
22. A percolator cover comprising a lid having an opening therein, a glass top having a portion thereof extending into said opening, spaced lugs 60
- on said top arranged peripherally thereof, and spring clips on said lid extending inwardly and downwardly into engagement with said lugs to hold said top in said lid but permitting unequal expansion of said top and lid without destroying the operative engagement of said spring clips with said lugs. 65
23. A glass percolator top comprising a body having a depending flange for insertion in an opening of a percolator lid, said flange having an outer peripherally extending bead for engagement with the upper surface of said lid and having the engaging surface thereof substantially in a single plane, said flange having a ledge extending peripherally there-about with different portions 10 thereof facing said engaging surface of said bead at different distances from said bead and merging gently with each other so as to provide various portions to be engaged by a retaining means on said lid to compensate for differences in sizes 15 and proportions in tops and lids. 20
24. A glass percolator top comprising a body having a depending flange for insertion in an opening of a percolator lid, said flange having an outer peripherally extending bead for engagement with the upper surface of said lid and having the engaging surface thereof substantially in a single plane, said flange having a ledge extending peripherally there-about with different portions 25 thereof facing said engaging surface of said bead at different distances from said bead and merging gently with each other so as to provide various portions to be engaged by a retaining means on said lid to compensate for differences in sizes 30 and proportions in tops and lids, 35
25. In a percolator cover, the combination with a lid having an opening therein for receiving a glass percolator top, a glass top arranged within said opening of means on said top for limiting movement of said top into said opening, and a removable continuous inextensible ring member having means thereon for engaging the underside of said lid and also a portion upon said top, whereby on relative rotation of said ring and top to 40 move said ring and top into operative clamping relation with respect to each other, the removal of said top from said opening is prevented, and said top is held firmly within said opening. 50
26. In a percolator cover, the combination with 55 a lid having an opening therein for receiving a glass percolator top, of a glass top, means on said top for limiting movement of said top into said opening, and a removable ring-like member having means thereon for engaging the underside 60 of said lid and also a portion on said top, whereby when said ring and top are in operative position, the accidental removal of said top from said opening is prevented, and said top is held firmly within said opening, said ring-like member 65 being arranged in operative position on said top either before or after insertion of said top into said opening.
27. A continuous ring of the class described, comprising a body portion and means extending 70 therefrom and arranged to contact a configuration on a percolator top to retain the same in the lid of a percolator. 75
28. A ring of the class described, comprising a body portion and means extending therefrom, 75

- said body portion being arranged to contact an apron on a percolator top, and the extending means at least one depression in said apron.
29. A percolator top having an apron and a bead thereabove for limiting movement of said apron into an opening in a percolator cover, said apron being provided with a circular abutment spaced from said limiting means, thus forming an annular depression between the limiting means and said abutment surface, a separate ring on said apron adapted to fit in said annular depression and also contacting the limiting bead, said ring having fingers thereon adapted to hold the top and cover together.
- 15 30. A percolator top retaining means comprising a ring, a rolled edge portion and integral spring fingers projecting therefrom.
31. In combination with a coffee pot lid having a central opening, a percolator top provided with a bead and an apron, said apron having an outwardly extending portion and a separate inextensible resilient ring encircling the apron above the extending portion, to lock the lid and top together.
- 25 32. A percolator top having an apron and a bead thereabove for limiting the movement of said apron into an opening in a percolator lid, said apron being provided with a depression below the outer surface thereof, a separate ring on said apron, a part thereof fitting in said depression and also contacting said limiting bead, said ring having fingers thereon adapted to hold the top and cover together.
33. In combination with a coffee pot lid having a central opening, a percolator top fitting within said opening, of a continuous ring of flexible material provided with spring means between the lid and top for securing them together.
- 40 34. In combination with a coffee pot lid having a central opening, and a percolator top to fit said opening, of a separate continuous ring of resilient material provided with spring fingers, the top having means engaging the spring fingers for locking the top and lid together.
- 45 35. In combination with a coffee pot lid having a central opening, and a percolator top to fit said opening, of a continuous ring of resilient material, provided with spring means, the top having means engaging the spring means for locking the top and lid together.
- 50 36. A coffee pot lid provided with a central opening and a percolator top fitting said opening, a separate spring means secured to the lid and depending around said opening, and means on the top for engaging said spring means to lock it to the lid.
37. In combination, a coffee pot lid having a central opening, a percolator top having a circular bead and a depending apron provided with
- an enlargement and a separate continuous resilient ring encircling the apron above said enlargement for retaining the lid and top in locked relation.
38. A coffee pot lid provided with an opening, a percolator top fitting said opening having an apron provided with a configuration thereon, separate spring means detachably carried by the apron, and provided with means for engaging the configuration to hold the lid and top together, and to hold said spring means on said top during and after insertion of said top into said opening, and said spring means being so shaped as to permit the insertion of said top into said opening while the spring means is so held in place on said top.
39. In combination, a coffee pot lid having a central opening, a percolator top, and a separate ring having inwardly projecting resilient means for co-action with means on the top, to retain the lid and top in locked relation.
40. In combination, a coffee pot lid having a central opening, a percolator top having a bead and a depending apron, a separate continuous ring provided with spring means for co-action with means on the apron, to retain the lid and top in locked relation.
41. A top for coffee pots having an apron and means thereabove for limiting movement of said apron into an opening in a percolator lid, the apron having a circular abutment or ledge spaced from said limiting means, thus forming an annular depression between the limiting means and the abutment or ledge.
- 45 42. A container cover having an opening, a percolator top having an apron and means thereabove for limiting movement of said apron into said opening, said apron being provided with a circular abutment spaced from said limiting means, thus forming an annular depression between the limiting means and said abutment, and a separate ring-like element inextensible when in place in said depression, to lock the top and cover together.
43. A percolator top having a portion to be received within an opening in a percolator lid provided with two annular abutment surfaces spaced from each other to form an annular retaining means receiving recess therebetween.
- 48 44. In combination with a coffee pot lid having a central opening, of a percolator top having a bead and a depending apron, said apron being provided with an abutment spaced from said bead and having one or more depressions in the space between said bead and said abutment, and a resilient ring having means coacting with said depression or depressions for locking said top and lid together.

EMIEL P. SEGHERS.
